UNITED STATES PATENT OFFICE

PIERRE CREUZÉ, OF PARIS, FRANCE, ASSIGNOR TO SOCIÉTÉ D'ÉTUDES SCIENTIFIQUES
ET INDUSTRIELLES, OF PARIS, FRANCE

RADIO VALVES EMPLOYING GALLIUM

Application filed May 27, 1930, Serial No. 456,255, and in France June 1, 1929.

Gallium is a white, hard, slightly malleable and strong metal; its density is 5.9 and its melting point 29.5° . It is readily fusible and can remain liquid as far as 0° .

5 It oxidizes but little and does not volatilize at all, even at a red heat. It unites all the conditions for obtaining an abundant emission of electrons with the aid of very low temperatures. Finally it possesses the property of adhering strongly to glass when it is molten.

Moreover, it is known that it is possible to cover a metallic filament with a very light layer of a glass having a high fusing point, 13 such as boro-silicate glass.

The object of the present invention is to employ gallium or its salts for constructing a valve which can be heated at extremely low temperatures either directly with continuous 20 or alternating current from the mains (with a transformer and resistance) or with battery or accumulator elements of very low power or by any external source of heat.

Nothing has to be modified in the existing 25 form and arrangements of radio valves excepting in the filament. The latter, which is of a suitable metal of suitable diameter, is covered with a layer of boro-silicate glass.

The filament covered with glass then receives a more or less thick coating of gallium 30 either by dipping in the liquid state and slowly cooling, or by pulverizing under a low pressure, or by a galvanoplastic or electrolytic process or by casting it, etc.

35 The invention will now be described with reference to the accompanying drawing in which:

Figure 1 is a sectional view of a filament according to the invention.

40 Figure 2 is a diagrammatic view of a radio valve embodying a filament according to the invention.

Figure 3 is a sectional view of a second form of filament according to the invention.

45 Figure 4 is a plan view of a modification of Figure 3.

Figure 5 is a section of a variant of Figure 3.

The arrangement shown in Figure 1 of the 50 drawing comprises a filament 1 made of suit-

able metal, a layer of glass 2 on this filament and a coating of gallium 3 covering the glass.

The filament thus prepared is then arranged in the claws of the filament supporting wires of a valve, and the subsequent operations for completing the valve are similar to those usually carried out (positioning the grid and the plate, creating the vacuum, etc.)

Figure 2 shows a diagrammatic sectional view of a valve comprising a filament such as that shown in Figure 1. In this figure, 4 and 5 are the leads to the filament 6, 9 is the grid and 10 the plate. Provision may be made of a transformer 7 and a resistance 8 contained in the base of the valve.

Instead of forming the filament as described above, the gallium may be arranged in the form of a solid or hollow disc in the interior of which the heating element is arranged.

Figure 3 shows a modification in which the metal heating filament 11, still covered with glass, is arranged in a solid or hollow disc of gallium 12.

In the case shown in this figure, the metal heating filament covered with glass is arranged across a diameter of the gallium disc; but it may also be arranged in the form of a spiral, as shown at 13 in the plan view in Figure 4.

In the example shown in Figure 5, the metal heating filament 14 is arranged inside a glass support 15 receiving the gallium disc 16.

In the case when it is desired to obtain the heating by other means than electricity, the source of heat may continue to be external, and be composed of vapours or hot air with a generator which may be a simple alcohol lamp or a petrol lamp with a temperature regulator.

This regulator may be formed by a simple strip of zinc or iron, closing the source of heat when the temperature reaches $30-31^{\circ}$, this regulation being similar to that employed in heating stoves using petrol or operated in any other way.

As will be seen, this valve permits with very different and numerous accessory heating means, very varied types of lamps to be obtained. These lamps are capable of permit-

ting numerous mountings which avoid the greater part of the dangers which are encountered in practice. They also permit the weight of apparatus and the overall dimensions to be reduced and to obtain detection and amplification under the most favorable conditions and also the rectification of alternating currents.

What I claim is:

- 10 1. A filament for radio valves composed of a metal coated with a layer of glass, the glass being in turn coated with a layer of gallium.
- 15 2. A filament for radio valves composed of a metal coated with a layer of fire resisting glass, the glass being in turn coated with a layer of gallium.

In testimony whereof I have signed my name to this specification.

20 PIERRE CREUZÉ.
